DESIGN FOR A TOOTHBRUSH

Harold Palmer Duey, Los Angeles, Calif.

Application April 6, 1940, Serial No. 91,517

Term of patent 14 years

To all whom it may concern:

Be it known that I, Harold Palmer Duey, a citizen of the United States and residing at Los Angeles, in the county of Los Angeles and State of California, have invented a new, original, and ornamental Design for a Toothbrush, of which the following is a specification, reference being had to the accompanying drawing, forming part thereof, in which:

Fig. 1 is a side elevational view of a toothbrush showing my new design;

Fig. 2 is a top plan view thereof,
Figs. 3, 4 and 5 are cross-sectional views on the lines 3—3, 4—4, and 5—5 respectively, of Fig. 2 and

Fig. 6 is an end elevational view thereof.

I claim:

The ornamental design for a toothbrush, as shown.

HAROLD PALMER DUEY.
